CLAIM

We claim the ornamental design for a health monitoring device with a button, as shown and described.

DESCRIPTION

FIG. 1 is a front perspective view of the health monitoring device with a button of the claimed design;

FIG. 2 is a front elevation view of the health monitoring device with a button shown in FIG. 1;

FIG. 3 is a rear elevation view of the health monitoring device with a button shown in FIG. 1;

FIG. 4 is a bottom plan view of the health monitoring device with a button shown in FIG. 1;

FIG. 5 is a top plan view of the health monitoring device with a button shown in FIG. 1;

FIG. 6 is a left side elevation view of the health monitoring device with a button shown in FIG. 1; and,

FIG. 7 is a right side elevation view of the health monitoring device with a button shown in FIG. 1.

The broken lines shown in the figures represent portions of the health monitoring device that form no part of the claimed design.

1 Claim, 7 Drawing Sheets
